UNITED STATES PATENT OFFICE.

JOHN L. WHEELER, OF ST. LOUIS, MISSOURI, ASSIGNOR TO THE MEASUREGRAPH COMPANY, OF ST. LOUIS, MISSOURI, A CORPORATION OF DELAWARE.

RESET-MECHANISM CONTROL FOR PRESSER ROLLERS.

Application filed May 19, 1922. Serial No. 562,255.

To all whom it may concern:

Be it known that I, JOHN L. WHEELER, a citizen of the United States, residing in the city of St. Louis and State of Missouri, have 5 invented new and useful Improvements in Reset-Mechanism Control for Presser Rollers, of which the following is a specification.

This invention relates to length indicating machines and in the following specification 10 it is described as applied to a fabric measuring and cost computing machine. In operating these machines, after a measurement has been taken the indicating mechanism must be reset to zero; the indicating mechanism is advanced by a measuring roller over 15 which the fabric is pulled, and during the measuring operation the fabric is pressed against the measuring roller by a presser roller. The indicating mechanism is reset 20 to zero after the presser roller has been raised. It sometimes happens that the operator will insert the fabric and let down the presser roller before resetting the mechanism, or, if reset, before the indicating 25 mechanism has completed its return to zero. This results, of course, in an excess indication of measurement.

The general object of the present invention is to provide an indicating or measuring 30 machine with means for overcoming this difficulty, and to this end to provide such a construction as will prevent the presser roller from being lowered until the machine has been reset and the mechanism fully returned to the zero position. Another object 35 of the invention is to provide means for raising the presser roller whenever the reset mechanism is operated, so as to prevent the clerk from resetting the mechanism without 40 raising the presser roller. With fabric in the machine and the pressed roller lowered, the clerk will thus be prevented from starting the reset and then beginning the measuring operation before the return to zero.

45 In one aspect the invention may be regarded as involving providing automatic means for preventing the operator from letting the presser roller down against the measuring roller until the resetting movement has been completed; and in another, as involving a control of the presser roller from the manually operated member which controls the resetting operation.

50 Further objects of the invention will appear hereinafter.

The invention consists in the novel features, and in the general combination of parts to be particularly described herein-after, all of which contribute to produce a simple and efficient reset mechanism control 60 for presser roller. A preferred embodiment of my invention will be particularly described in the following specification, while the broad scope of my invention will be pointed out in the appended claims. 65

In the drawing, Figure 1 is a plan of a machine embodying my invention;

Figure 2 is a side elevation of this machine with the casing removed; 70

Figure 3 is an elevation of the opposite side from that shown in Figure 2 with a portion of the framing broken away;

Figure 4 is a horizontal section taken about on the line 4—4 of Figure 2; 75

Figure 5 is an elevation showing the right hand end of the machine as illustrated in Figure 3;

Figure 6 is a vertical section through the machine taken about on the line 6—6 of 80 Figure 2;

Figure 7 is a vertical section through the machine taken about on the line 7—7 of Figure 2; and

Figure 8 is a vertical section through 85 the machine taken about on the line 8—8 of Figure 2.

The machine comprises a casing 1 in the upper portion of which windows are provided through which charts 2, 2 are visible. 90 The numbers on the charts come into position opposite two scales 3. These scales indicate price rates for fabric which the machine may be used to measure, and constitute part of the indicating mechanism. 95 These charts are driven during the measuring operation by a measuring roller 4 which operates through a train of gears 5 (see Fig. 8) to drive the shafts 6 of two rollers 7. The ends of the charts 2 wrap upon the rollers 7 during the measuring operation and become unwrapped from a supply roller or drum 8 which has an internal spring 9 operating to maintain tension in the charts and also operating to return the charts to zero after the measuring operation. 100

The gear train 5 includes a large gear 10 (see Fig. 8) the horizontal shaft 11 of which carries a bevel gear 12 (see Figs. 2 and 3) 110

which meshes with a corresponding bevel gear 13 carried on a vertical shaft 14. This tubular shaft 14 extends upwardly and carries a fast moving pointer 15. Through a suitable reduction gear 16 (see Fig. 2) the shaft 14 drives a large tubular shaft or sleeve 17, the upper end of which carries a slow moving pointer 18. These pointers, therefore, move in synchrony with the charts and pass around on the face of a dial 19 which indicates up to twelve yards, and also indicates fractions of a yard. In the present instance this dial indicates eights of a yard.

After a measuring operation, the desired length of fabric is marked or notched on its edge to indicate the point where it is to be cut off. This is accomplished by means of a marking device or shears including a marking lever or knife lever 20 (see Fig. 2) which carries a blade 21 to co-operate with a fixed blade 22. The fabric in being measured is pulled through a gap 23 in the machine so that it passes over the measuring roller 4, and while the measuring operation is taking place the fabric is held against the measuring roller by means of a presser roller 24 (see Fig. 7) which is carried on a rock frame 25 and which may be held against the measuring roller by a pair of springs 26.

The rocking frame 25 is mounted to rock on a rock shaft 27, the ends of which are rotatable in vertical frame plates 28 and 29. (See Fig. 4.)

When the presser roller is raised a latch 30 operates to hold it raised. For this purpose the rocking frame 25 is provided with an arm 30 which extends outwardly to co-operate with a latch 31 (see Fig. 4) which is pivoted at 32 and which carries a spring 33 tending to move the latch into a position to engage the arm. When the arm 30 moves downwardly into the position in which it is shown in Fig. 2 it will move down along the vertical edge 34 of the latch 31 and will eventually arrive under a shoulder 35. When this occurs the spring 33 will pull the latch over so that the shoulder 35 engages over the arm, and this will hold the presser roller up. When it is desired to release the presser roller this may be accomplished by pressing inward upon a thumb plate or lever 36 which constitutes an operating arm for the latch. When the knife lever 20 is actuated, its edge 20^a engages arm 30 and raises the presser roller until the latch 31 holds it up.

Suitable means is provided for effecting the resetting of the indicating mechanism to zero. In the present instance the resetting movement is accomplished by utilizing the spring 9 of the roller 8 (see Fig. 7) as the resetting means. However, in order to enable this spring to accomplish this result it is necessary to open the driving train. In order to accomplish this I provide a clutch shaft 37 in the gear train 5 (see Figs. 3 and 8). This shaft carries a gear wheel 38 which is driven by a pinion 39 on the shaft of the measuring roller. The clutch shaft or stem 37 has its inner end mounted to slide in the vertical frame plate 29. It also carries rigidly a pinion 40 which operates as a clutch member to co-operate with the adjacent face of the gear wheel 38, the operation being such that if the stem or clutch shaft 37 is shoved inwardly it will open the friction clutch which comprises the two gear wheels 38 and 40. A coil spring 41 disposed around the inner end of the shaft 37 normally holds the clutch closed. The gear or pinion 40 meshes with the large gear wheel 10 referred to above which drives the shaft 11, the inner end of the shaft 11 being provided with a gear wheel 42 which meshes with an idler 43, said idler meshing with two pinions 44 which are carried, respectively, by the shafts 6 of the two rollers 7. This clutch mechanism and driving train is fully described in application Ser. No. 513,303, in the name of George B. Kyle, filed November 7, 1921 on fabric measuring and cost computing machine. The shaft or stem 37 is guided to slide in suitable brackets 45. The clutch may be opened at will by means of a hand operated resetting member 46 in the form of a flat stem, the outer portion of which is guided to slide through a vertical bracket plate 47 (see Figs. 2 and 3). The side of this stem 46 is connected by a link 48 with a lever 49 having a laterally bent flange or pusher 50 which engages the end of the shaft 37. The inner end of the stem 46 is supported by means of a slot 51 in the stem which is engaged by a pin 52 which projects from the side of the lever 49. The upper end of the lever 49 is pivotally supported by a horizontal frame plate 53.

The resetting stem 46 has a thumb head 54 which is accessible through the wall of the casing 1. When the stem 46 is shoved inwardly the clutch will be opened and the spring 9 will then return the indicating mechanism to zero. When this occurs the resetting stem will be automatically locked in a position to hold the clutch open and will also actuate means to prevent the presser roller from being let down upon the measuring roller until the resetting movement is completed. For this purpose I provide a detent pawl 55 (see Fig. 3) which is pulled by a spring 56 so that when a notch 57 comes under the pawl, the pawl will move down into the notch and hold the stem 46 against being returned by the action of its return spring 58. In addition to this the inner end of the stem 46 carries a pin 59 which operates in a slot 60 on the lower end of an arm 61 of a bell crank lever Figs. 2 and 3, said bell crank lever having a horizontal arm 62 which extends over and pro-

jects into a slot 63 (see Fig. 8) in the upper end of a sliding plate 64 held near the face of the frame plate 29 and guided thereon by means of a pin 65 and slot 66.

5 This plate 64 is connected with the presser roller frame and when the stem 46 is locked against return by the pawl 55 the arm 62 will operate to prevent the plate 64 from descending, and by reason of the connection 10 between the plate 64 and the presser roller frame this will operate to prevent the presser roller frame from moving to let the presser roller come against the measuring roller. In order to accomplish this the plate 15 64 has a horizontal arm 67 which has a loose pin connection 68 with the outer end of an arm 69, and this arm 69 is rigidly attached to the end of the rock shaft 27 which comes through the vertical frame plate 29. (See 20 Fig. 4.) With this arrangement it will be evident that if the latch 31 is released when the stem 46 is shoved in, the presser roller 25 24 will not descend and come against the measuring roller 4 because this movement will be prevented by the plate 64 co-operating with the arm 62.

It will also be evident that if the presser roller should be down against the measuring roller when the resetting button or head 54 30 is pressed, then the arm 62 would operate to raise the presser roller 24 and the latch 31 would operate to latch it in its elevated position.

Automatic means is provided for releasing 35 the detent pawl 55 when the indicating mechanism arrives at the zero position. In order to accomplish this the detent pawl 55 has a substantially vertical arm 70. (See Fig. 3.) This arm 70 is engaged by a horizontal arm 71 (see Fig. 6) which is carried 40 on a vertical rock shaft 72. (See Fig. 4.) On the tubular shaft or sleeve 17 there is mounted rigidly an arm 73 which consequently rotates with the slow moving pointer 18 45 and completes one revolution when the hand 18 has made one revolution. The end of this arm 73, when the mechanism arrives at the zero position strikes against a dog 74 which is rigidly attached to the vertical rock shaft 50 72. This rocks the shaft 72 in a clock-wise direction and causes the arm 71 to actuate the arm 70 and release the pawl. A light coil spring 75 (see Fig. 4) is attached to an arm 76 rigid with the rock shaft 72 and normally holds the arm 71 back so that it will 55 not interfere with the movement of the detent pawl 55 when it moves down to engage the notch 57. The arm 67 Fig. 8 is connected by a spring 77 with a brake plate 78 60 guided on the face of the frame plate which, when the presser roller is raised, comes against a disk 79 on the measuring roller shaft, and holds the same against rotating.

The mode of operation of the entire ma-

chine will now be briefly described. While 65 the presser roller 24 is in its raised position the operator introduces the cloth or fabric between the presser roller and the measuring roller 4. He then presses upon the lever 36 (see Fig. 2) and this releases the presser roller frame and permits the springs 26 Fig. 7 to pull the presser roller 24 down upon the measuring roller 4. The operator then pulls the fabric through the machine and by doing this the pinion 39 Fig. 8 on the measuring 75 roller shaft drives the gear train 5, which operates to advance the charts 2 and the pointers 15 and 18. After the measuring operation the operator may operate the lever 20 to mark the fabric at the point where it 80 is to be cut off. When this takes place the edge 20^a of the lever 20 will engage the arm 30 of the presser roller frame and operate to raise the presser roller. As the presser roller rises the arm 30 will be engaged by the 85 shoulder 35 of the latch 31 and the presser roller will be held elevated.

The operator can then remove the web or cloth which he is measuring, from between the rollers 24 and 4. The operator next 90 shoves in on the resetting stem 46 which operates to open the clutch composed of the clutch members 38 and 40 (see Fig. 3); as the stem 46 moves inwardly the spring 56 pulls the detent pawl 55 down into the notch 57 and locks the clutch open.

The clutch stays open until the indicating mechanism has arrived at the zero position; when this occurs the arm 73 (see Fig. 4) will strike against the dog 74 and rock the vertical rock shaft 72. This will rock the arm 71 in a clockwise direction and it will engage the arm 70 Fig. 3 and release the detent pawl 55. In case the operator moves the latch 31 Fig. 4 with the intention of letting the 100 presser roller down onto the measuring roller before the indicating mechanism has arrived at zero, the presser roller will not descend onto the measuring roller because it will be held up by the arm 62 (see Figs. 2, 3 and 8) which will engage the plate 64 and hold the same up, thereby holding up the arm 69 and preventing the rock shaft 27 from rotating in the direction which it would have to rotate in if it were moving in 115 the direction to carry the presser roller down onto the measuring roller.

It will also be evident that if the resetting stem 46 is operated while the presser roller 24 is in its depressed position the arm 62 will 120 raise the plate 64 and operate through the arm 69 to rock the rocking frame 25 thereby raising the presser roller; in this case the latch 31 will operate in the usual way to hold the presser roller raised.

It is understood that the embodiment of the invention described herein is only one of the many embodiments my invention may

take, and I do not wish to be limited in the practice of my invention nor in my claims, to the particular embodiment set forth.

What I claim is:

- 5 1. In a fabric measuring and cost computing machine, the combination of indicating mechanism, a measuring roller for driving the same, a presser roller mounted so as to move toward or from the measuring roller, 10 resetting means for resetting the indicating mechanism to zero, a hand-actuated resetting member for controlling the same, and means actuated by the resetting member to prevent the presser roller from coming 15 against the measuring roller during the resetting movement of the indicating mechanism.
2. In a fabric measuring and cost computing machine, the combination of indicating 20 mechanism, a measuring roller, a clutch through which the measuring roller drives the indicating mechanism, a presser roller mounted so as to move toward or from the measuring roller, resetting means for resetting the indicating mechanism to zero when the clutch is open, a hand-actuated setting member for opening the clutch to permit the resetting means to reset the indicating mechanism to zero, and means actuated by the resetting member to prevent the presser roller from coming against the measuring roller during the resetting movement of the indicating mechanism.
3. In a fabric measuring and cost computing machine, the combination of indicating 35 mechanism, a measuring roller, a clutch through which the measuring roller drives the indicating mechanism, a presser roller mounted so as to move toward or from the measuring roller, resetting means for resetting the indicating mechanism to zero when the clutch is open, a hand-actuated resetting member for opening the clutch to permit the resetting means to reset the indicating mechanism to zero, means actuated by the resetting member to prevent the presser roller from coming against the measuring roller during the resetting movement of the indicating mechanism, and automatic means for holding the clutch open until the indicating mechanism has returned to zero.
4. In a fabric measuring and cost computing machine, the combination of indicating 50 mechanism, a measuring roller, a clutch through which the measuring roller drives the indicating mechanism, a presser roller mounted so as to move toward or from the measuring roller, resetting means for resetting the indicating mechanism to zero when the clutch is open, a hand-actuated resetting member for opening the clutch to permit the resetting means to reset the indicating mechanism to zero, means actuated by the resetting member to prevent the presser roller

from coming against the measuring roller 65 during the resetting movement of the indicating mechanism, means for holding the clutch open until the indicating mechanism has returned to zero, and means actuated by the mechanism of the machine as it arrives 70 at the zero position to release the clutch-holding means and permit the clutch to close.

5. In a fabric measuring and cost computing machine, the combination of indicating 75 mechanism, a measuring roller for driving the same, a presser roller to cooperate with the measuring roller, a presser roller frame carrying the presser roller and mounted so as to move the presser roller from or down against the measuring roller, 80 resetting means for resetting the indicating mechanism to zero, a hand-actuated resetting member for controlling the same, and means actuated by the resetting member to present downward movement of the presser 85 roller frame during the resetting movement of the indicating mechanism.

6. In a fabric measuring and cost computing machine, the combination of indicating 90 mechanism, a measuring roller, a clutch through which the measuring roller drives the indicating mechanism, a presser roller mounted so as to move toward or from the measuring roller, resetting means for resetting the indicating mechanism to zero when the clutch is open, a hand-actuated resetting member for opening the clutch to permit the resetting means to reset the indicating mechanism to zero, means actuated by the resetting member to prevent the presser roller from coming against the measuring roller during the resetting movement of the indicating mechanism, said resetting member having a stem with a notch therein, a detent 100 pawl to engage the notch when the resetting member is moved into a position to open the clutch, and means actuated by a part moving with the indicating mechanism for actuating the detent pawl to permit the clutch to close when the indicating mechanism has returned to zero.

7. In a fabric measuring and cost computing machine, the combination of indicating 115 mechanism, a measuring roller, a clutch through which the measuring roller drives the indicating mechanism, a presser roller, a presser roller frame carrying the same to enable the presser roller to move from or down against the measuring roller, resetting means for resetting the indicating mechanism to zero when the clutch is open, a hand-actuated stem for opening the clutch to permit the resetting means to reset the indicating mechanism to zero, means actuated by the said stem to prevent the presser roller from coming against the measuring roller during the resetting movement of the indicating mechanism, detent means for 120 125

locking the clutch in its open position and automatic means for releasing the said detent means when the indicating mechanism has returned to zero.

- 5 8. In a fabric measuring and cost computing machine, the combination of indicating mechanism, a measuring roller for driving the same, a presser roller mounted so as to move toward or from the measuring roller, resetting means for resetting the indicating mechanism to zero, a hand-actuated resetting member for controlling the same, and means actuated by the resetting member for moving the presser roller away
- 10 from the measuring roller.
- 15 9. In a fabric measuring and cost com-

puting machine, the combination of indicating mechanism, a measuring roller for driving the same, a presser roller mounted so as to move toward or from the measuring roller, resetting means for resetting the indicating mechanism to zero, a hand-actuated resetting member for controlling the same, a latch for holding the presser roller away from the measuring roller, and means actuated by the resetting member for moving the presser roller away from the measuring roller to enable the latch to operate.

In testimony whereof, I have hereunto set my hand.

JOHN L. WHEELER.
